UNITED STATES PATENT OFFICE.

WILLIAM BUTTLER, OF REDKEY, INDIANA.

DESIGN FOR A LAMP-CHIMNEY.

SPECIFICATION forming part of Design No. 30,250, dated February 21, 1899.

Application filed January 16, 1899. Serial No. 702,372. Term of patent 7 years.

To all whom it may concern:

Be it known that I, WILLIAM BUTTLER, of Redkey, in the county of Jay and State of Indiana, have invented a new and original 5 Design for Lamp-Chimneys, of which the following is a full, clear, and exact description, reference being had to the accompanying drawing, forming part of this specification, which represents in side elevation a lamp- 10 chimney embodying my design.

The leading feature of my design consists in a lamp-chimney having intermediate of its length an annular outwardly-swelled portion in somewhat the form of a globe, the chimney extending above this swelled portion.

15 In the drawing, 2 represents the cylindrical body of a chimney, having near its upper

end the annular outwardly-swelled portion 3 and extending upwardly from the swelled portion with a reduced diameter in the upper 20 portion 4. I have shown the swelled portion as frosted in the part marked *a* and the upper portion as provided with a bead or rib 5 and with edge ornamentation 6.

I claim—

25 The design for a lamp-chimney, substantially as herein shown and described.

In testimony whereof I have hereunto set my hand.

WILLIAM BUTTLER.
